UNITED STATES PATENT OFFICE

ROBERT O. FERGUSON, OF BRISTOL, TENNESSEE, ASSIGNOR OF ONE-HALF TO BERT E. ELLIOTT AND FRANK M. ELLIOTT, BOTH OF DETROIT, MICHIGAN

HYGIENIC CABINET

Application filed December 30, 1929. Serial No. 417,490.

This invention relates to hygienic cabinets, and more particularly to cabinets for holding in convenient form various articles which may be needed immediately in a household, as in the case of illness.

An important characteristic of this invention resides in a cabinet which is particularly constructed and arranged, or is equipped with special devices for, supporting a fountain syringe, and its several attachments, and also a plurality of sizes of hot water bags, and one or more ice bags. These several articles are ordinarily scattered and located at various places about the room, but under this invention means are provided within a small compass for supporting them in close juxtaposition, and whereby in the case of sudden illness, a physician, nurse, or other person in attendance upon the patient, will be able to have immediate access to any one, or all of said articles, and without loss of time in searching for any of them.

With the above, and other important objects in view, a particular feature of novelty and importance of the invention, is found in the means for supporting, in convenient position for use, the ordinary household fountain syringe. It is contemplated that by such means, the reservoir or bag is sustained in a normal position for use, while the discharge tube, which carries the nozzle, is so stored within the cabinet that it may be instantly removed in position for use, without disturbing the support for the bag. The preferred means for accomplishing this comprises a curved supporting device or devices, which are arranged to follow substantially the curved line of the top portion of the cabinet, certain of said devices being disposed within the device first mentioned, in order to properly support the terminal portion of the coil of the discharge tube, and prevent the formation of abrupt bends or kinks, which would tend to destroy the tube.

The novel features of the invention will be best understood from the following detailed description, when considered in connection with the accompanying drawings, in which:

Fig. 1 is a perspective view of a cabinet

embodying the features of my invention, the door being open;

Fig. 2 is a similar view of the cabinet with the door closed; and

Fig. 3 is a horizontal section thereof.

The cabinet is herein shown as composed of a back 1, a curved rim 3 constituting the sides, and a door 5 hinged to the rim 3 at 4, and provided with a suitable latch device 7 for holding the door closed.

Interiorly, the cabinet is provided on its back 1, with a hook or nail 8, for supporting the bag of a fountain syringe B, which is thus suspended in normal vertical position therein. The discharge tube or pipe T which leads from the lowermost portion of the bag B, and is provided with the usual threaded device for connection with any one of the usual nozzles N, is supported within the cabinet by one or more hook-shaped brackets 10. It will be seen that these brackets, beginning with the first of the series, as shown at the extreme upper left hand portion of Fig. 1, are so arranged in the top of the cabinet as to substantially follow a curved line corresponding to the curvature of the upper portion of the cabinet, whereby the discharge tube may be lead upwardly along the vertical side wall of the cabinet and thence in coiled form around, and following the outline of, the upper curved side of the cabinet wall 3, the tube being then crossed in front of the bag and its terminal portion supported by the two brackets 10 which are shown, in dotted lines, within the line of brackets first described, so as to support the end portion of the coiled tube in position for conveniently inserting the nozzle inside of the open mouth of the bag. By thus supporting the bag of the fountain syringe and its discharge tube, it will be readily seen that the syringe will be always in condition for immediate use, that is when the cabinet is supported suitably in vertical position, as shown in Fig. 1. If needed, the bag may be filled with liquid while so supported within the cabinet, and the discharge tube by merely pulling the same outwardly to disengage it from the brackets 10, will be at once available, the bag and its discharge tube being

always maintained in a position which will prevent the formation of any abrupt bends or kinks in the rubber tubing, to interfere with its use or shorten its life for useful purposes, it being understood that rubber if maintained in distorted or unduly bent condition, soon loses its elasticity and cracks, causing leakage.

In addition to the means for supporting the fountain syringe as above described, the interior of the cabinet is shown as provided with a plurality of forked brackets 12. Some of these are for the purpose of supporting the various nozzles N for the fountain syringe, while other brackets support the different types of syringes S, S', which may be needed at various times.

The door 5 is shown as provided exteriorly with a mirror 6, preferably having its edges formed with a plurality of faces 6', for ornamental purposes, or being otherwise formed in outline. The interior of the door carries a hook, screw, or other supporting device 14 for holding a plurality of hot water bags H, of different sizes, and also if desired, an ice bag I. These several devices hang from the same support 14, and when the cabinet door is thrown open as shown in Fig. 1, it will be readily seen that each and every one of these devices which are needed frequently in the sick room, are available for use simultaneously with the several syringes which are located in the body of the cabinet. The cabinet as an entirety, therefore, includes within its walls a complete set of the usual syringes, water bags and ice bags, which devices are all housed together and in such convenient manner as to render it unnecessary to lose valuable time in searching for any one of such devices, in a case of illness.

The right is reserved to make such changes and modifications in the details of construction of the device as herein disclosed, as will be comprehended by the following claims.

45 I claim:—

1. A cabinet having a back wall, means for supporting a fountain syringe in vertical position on said wall, comprising a device for sustaining the bag of the syringe, means for supporting the discharge tube in curved form arranged above said device and constructed to permit the tube to be coiled about the mouth of the bag, and additional means for supporting, in curved form, the terminal portion of the discharge tube in position for the nozzle to be held within the mouth of the bag, said additional means being arranged below and within the first-named supporting means.

60 2. A cabinet having enclosing walls, means for supporting a fountain syringe on one of said walls, comprising a device for sustaining the bag of the syringe, means for supporting the discharge tube in curved form arranged above said device and constructed

to permit the tube to be coiled about the mouth of the bag, and additional means for supporting, in curved form, the terminal portion of the discharge tube in position for the nozzle to be held within the mouth of the bag, said additional means being arranged below and within the first-named supporting means.

In testimony whereof I have hereunto set my hand this 28 day of December, A. D. 1929. 70 75

ROBERT O. FERGUSON.
